DESIGN FOR A BEAUTY PARLOR CHAIR

Irene N. Duncan and Roswell C. Duncan,
Whittier, Calif.

Application May 10, 1940, Serial No. 92,273

Term of patent 7 years

To all whom it may concern:

Be it known that we, Irene N. Duncan and Roswell C. Duncan, citizens of the United States and residing at Whittier, in the county of Los Angeles and State of California, have invented a new, original, and ornamental Design for a Beauty Parlor Chair, of which the following is a specification, reference being had to the accompanying drawing, forming a part thereof.

In the accompanying drawing:

Fig. 1 is a side elevational view of a beauty parlor chair showing our new design;

Fig. 2 is a front elevational view; and

Fig. 3 is a rear elevational view.

We claim:

The ornamental design for a beauty parlor chair, substantially as shown.

IRENE N. DUNCAN.
ROSWELL C. DUNCAN.
